UNITED STATES PATENT OFFICE.

JOSEPH FIRNER, OF PRESCOTT, WISCONSIN.

WINDOW-SASH HANGER AND OPERATOR.

1,193,677.

Specification of Letters Patent. Patented Aug. 8, 1916.

Application filed October 2, 1915. Serial No. 53,701.

To all whom it may concern:

Be it known that I, JOSEPH FIRNER, a citizen of the United States, residing at Prescott, in the county of Pierce and State of Wisconsin, have invented certain new and useful Improvements in Window-Sash Hangers and Operators; and I do hereby declare the following to be a full, clear, and exact description of the invention, such as will enable others skilled in the art to which it appertains to make and use the same.

My invention has for its object to provide an improved window sash hanger and operator; and, to this end, it consists of the novel devices and combinations of devices herein-after described and defined in the claims.

In the accompanying drawings, which illustrate the invention, like characters indicate like parts throughout the several views.

Referring to the drawings, Figure 1 is a vertical section taken centrally through a window frame and sash having the invention incorporated therein, some parts being shown in different positions by means of broken lines; Fig. 2 is a fragmentary view in section taken on the line $x^2 x^2$ of Fig. 1; Fig. 3 is a detail view, partly in plan and partly in horizontal section, taken on the line $x^3 x^3$ of Fig. 1; Fig. 4 is a fragmentary view in side elevation with some parts shown in section; Fig. 5 is a right side elevation of the parts shown in Fig. 4, some parts being sectioned on the line $x^5 x^5$ of Fig. 4; Fig. 6 is a view corresponding to Fig. 1, with the exception that the window sash is shown in a different position; and Fig. 7 is a detail view in elevation, looking in direction of the arrow marked on the line $x^7 x^7$ of Fig. 2, with the window sash in the position illustrated in Fig. 4.

The numeral 1 indicates a window frame having side sash stops 2, a top sash stop 3 and a window sill 4, which affords the bottom or lower sash stop. Movably mounted in the window frame 1 and normally seated against the stops 2 and 3 and window sill 4, is a single window sash 5.

The window sash stops 2 are, as shown, constructed from metal and each thereof has, in its face against which the window sash 5 bears, a guide channel 6 that is T-shape in cross section. Each sash stop 2 also com-

prises a relatively long upper section and a relatively short lower section, the latter being connected to the former by a hinge 7 for inward swinging movement, as shown in Fig. 6. The upper sections of the sash stop 2 are provided with inwardly projecting flanges 8, that have flat engagement with the window frame 1 and are rigidly secured thereto by screws 9. Turnbuttons 10, pivoted to the upper sections 8 of the sash stops 2, for engagement with the lower sections thereof, are provided for normally holding said lower sections in line with said upper sections, as shown in Fig. 1.

The window sash 5 is connected by a pair of short links 11 to the sash stops 2, for compound sliding and pivotal movements, and which links also permit the said sash to be reversed side for side by an end for end movement. These links 11 are pivoted in transverse notches 12, cut in the upper ends of the stiles of the window sash 5. The outer ends of the links 11 are provided with T-heads 13, mounted in the channel guides 6 for sliding and pivotal movements, as best shown in Fig. 3. Obviously, the T-heads of the links 11 are interlocked with the correspondingly formed channel guides 6 against lateral separation therefrom. As the links 11 hold the upper end of the window sash 5 close to the side stops 2, the upper longitudinal edges of said window sash 5 are rounded, as best shown in Figs. 1 and 2, to permit the same to be turned end for end.

The window sash 5 is intermediately connected to the window frame 1 by a long link 14. One end of this link 14 is pivoted at 15 to one of the stiles of the window sash 5 and the other end thereof is pivoted at 16 to a face plate 17. This face plate 17 is set into and secured by screws 18 to the adjacent side of the window frame 1 and covers a pocket 19 formed in said frame. The link 14, during swinging movement of the window sash 5, permits the T-heads 13 to slide and move pivotally in the channel guides 6.

When it is desirable to reverse the window sash 5, side for side, the lower end thereof is first swung outward and its upper end is moved downward on the sash stops 2, until said sash 5 assumes a position, as shown by full lines in Fig. 6. However, before the

window sash 5 can be moved into this position, it is necessary to release the turn buttons 10 to allow free swinging movement of the lower sections of the sash stops 2. 5 Then by an upward movement, of the outer end of the window sash 5, and further downward sliding movement of its inner end, said sash is moved into a position as indicated by broken lines in Fig. 6, or if desired, the window sash may be moved closer to the window frame 1. Owing to the difference in the distances between the pivots 15 and 16 of the link 14 and the pivot 15 and the T-heads 13, it is, of course, obvious why it is necessary to 10 make the lower sections of the sash stops 2 movable, while the window sash 5 is being turned from a horizontal into a vertical position.

The following connections are provided 20 for swinging the link 14 on its pivot 16 and for holding the same in different set positions; and hence, for imparting the compound sliding and pivotal movements to the window sash 5, which are necessary to open 25 and close the same and for turning the same side for side. Rigidly secured to the link 14, near its lower end, is a laterally projecting stud 20, which projects into the pocket 19 through a segmental slot 21, formed in the 30 face plate 17. A horizontally extended feed screw 22, having an angular end, is mounted in the pocket 19 and journaled in bearings 23, secured to the window frame 1. Mounted in the window frame 1 and axially aligned 35 with the feed screw 22, is a socket 24 into which the angular end of said screw projects. The feed screw 22 is turned by a socket wrench 25, adapted to be inserted into the socket 24, and applied to the angular 40 end of said screw. A nut block 26 is mounted on the feed screw 22 and is pivotally connected to the stud 20 by a short link 27. The link 27 also holds the nut block 26 against rotation, during its traveling 45 movement on the feed screw 22.

By means of the feed screw 22, the window sash 5 may be tightly drawn against the stops 2 and 3 and the window sill 4; thus affording a weather-tight joint between 50 the window frame and sash. By reversibly mounting the window sash 5, it is possible to wash, paint or repair the same from the inside of a building. When the window sash 5 is open, as shown in Fig. 1, or when 55 the same is only slightly out of its true horizontal position, the same will shed rain. A window sash, mounted in accordance with the above described invention, has all of the advantages of a casement window, in 60 that the entire window sash may be opened, which is not possible with windows having upper and lower sliding sashes. When the wrench 25 is removed from the feed screw 22, the window sash 5 is securely locked in 65 a closed position, or it may be locked in an

open position, which open position, however, need not be of a size sufficient to permit a person to pass through the window from the outside.

What I claim is:—

1. The combination with a window frame, of a window sash secured to the window frame for compound sliding and pivotal movements, a link pivotally connecting the window sash to the window frame and permitting said window sash to be reversed end for end, and a self-locking device for imparting swinging movement to the link and for holding the same in different set positions. 70

2. The combination of the window frame, of a window sash secured to the window frame for compound sliding and pivotal movements, a link pivotally anchored at one end to the intermediate portion of the window sash and at its other end to the window frame, said link permitting the window sash to be reversed end for end, and a self-locking device for imparting swinging movement to the link and for holding the same 75 80 85 90

95 100 105 110 115 120 125 130

3. The combination with a window frame, of a window sash secured to the window frame for compound sliding and pivotal movements, a link pivotally connecting the window sash to the window frame and permitting said window sash to be reversed end for end, a feed screw mounted on the window frame and having a traveling nut block, and a connection between the link and nut block.

4. The combination with a window frame, of a window sash, secured to the window frame for compound sliding and pivotal movements, a link pivotally connecting the window sash to the window frame and permitting said window sash to be reversed end for end, a feed screw mounted on the window frame and having a traveling nut block, a connection between the link and nut block, and a stop limiting the pivotal movement of 105 110 115 120 125 130 the link with respect to the window sash.

5. The combination with a window frame having guides with movable sections, of a window sash secured at one end to the guides for compound sliding and pivotal movements, a link pivotally connecting window sash, at its intermediate portion to the window frame, the movable sections of the guides permitting the window sash to be reversed end for end during its sliding and 115 120 125 130

135 140 145 150 155 160 165 170 175 180

6. The combination with a window frame having guides with movable sections, of a window sash secured at one end to the guides for compound sliding and pivotal movements, a link pivotally connecting window sash, at its intermediate portion to the window frame, the movable sections of the guides permitting the window sash to be reversed end for end during its sliding and

pivotal movements, and means for locking the movable sections of the guides in alignment with the main sections thereof.

7. The combination with a window frame 5 having vertical sash stops with guide channels formed therein that are T-shaped in cross section, of a window sash, and links pivoted to the window sash for movement from one side to the other of the window

sash and having T-heads mounted in the 10 channel guides for sliding and pivotal movements.

In testimony whereof I affix my signature in presence of two witnesses.

JOSEPH FIRNER.
